UNITED STATES PATENT OFFICE.

CORNELIUS C. HASTINGS, OF SPRINGFIELD, MASSACHUSETTS, ASSIGNOR TO MILTON BRADLEY COMPANY, OF SPRINGFIELD, MASSACHUSETTS, A CORPORATION OF MASSACHUSETTS.

LOCKING DEVICE FOR LEGS OF TABLES.

963,439.

Specification of Letters Patent.

Patented July 5, 1910.

Application filed February 5, 1910. Serial No. 542,232.

To all whom it may concern:

Be it known that I, CORNELIUS C. HASTINGS, a citizen of the United States of America, residing at Springfield, in the county of Hampden and State of Massachusetts, have invented new and useful Improvements in Locking Devices for Legs of Tables, of which the following is a specification.

10 The invention relates to locking devices for table-legs.

This invention relates to locking devices a structure that will effectually lock the leg of the table either in its folded or open position, and one that is easy to operate and yet will not become displaced when in use.

Broadly the invention consists (1) in providing a sliding element having lugs thereon that are adapted to engage a groove in a casting that is attached to the leg of the table, one of the lugs being adapted to engage the groove when the leg is in an unfolded position, and another lug to engage the same groove when the leg is folded; 25 and (2) in providing a latch for locking the slide against accidental displacement when the leg is unfolded or in a vertical or supporting position.

The invention will be fully set forth in 30 the specification and drawings forming a part thereof, and particularly in the claims.

In the drawings.—Figure 1 shows an end view of a table with the leg locked in the open or supporting position and the latch 35 on the sliding bolt for retaining the slide against movement. Fig. 2 is a vertical, sectional view on the line 2—2 of Fig. 1 clearly indicating the locking lug on the bolt in engagement with the groove in the head 40 portion of the casting that is attached to the leg. Fig. 3 shows a sectional view similar to that shown in Fig. 2 with the leg in the folded position, and the groove in the casting engaged by the other lug on the 45 sliding bolt. Fig. 4 is a bottom plan view of the table showing a portion of the leg in section on the line 4—4 of Fig. 1, looking in the direction of the arrow and indicating the position of the locking device with 50 the leg in the open or unfolded position. Fig. 5 is a perspective view of the locking device showing the leg in the open position and the lug on the locking bolt in engagement with the groove in the casting at-

tached to the leg, and with a portion of the 55 cap element that confines the movement of the locking bolt broken away.

Referring to these drawings in detail, *a* designates the top portion of the table; *b* one of the legs thereof; *c* a cleat element 60 suitably secured to the underside of the table top. Secured to the bottom side of the table-top *a* is an angle-shaped casing *d* which is provided with an offset portion *e* whereby a space is provided between the 65 offset portion and the table, as shown at *e'*, in which space is located the locking bolt or sliding element *f* which is provided with two locking lugs *g* and *h*,—the lug *g* being adapted to enter the groove *i* in the head 70 portions of the casting *j* which is attached to the leg *b* by any suitable means, as the screws *k*. The leg *b* of the table-top is attached thereto by means of the hinges *n*, as clearly illustrated in Fig. 5. The casting *j* 75 is provided with a disk-shaped head portion *m* in which the groove *i* is located.

Integral with the slide *f* is an operating handle *o* which extends at right angles to the slide *f* and over the cleat portion *c*, as indicated in Figs. 4 and 5. This handle is for the purpose of moving the slide so as to lock the leg either in a folded or open position.

Pivotedly mounted on the inner end portion of the handle element *o* is an L-shaped 85 latch *p* having a notch *q* in one of the arms thereof, which latch engages the shoulder portion *r* of the opening *d'* in the casing *d* in order that the slide *f* may not be accidentally moved and thereby withdrawing 90 the lug *g* from the groove *i* and unlocking the leg. The weighted portion of the latch *p*, when the leg is in use, normally throws the notch *q* against the portion *r*.

As shown in Fig. 5, the leg is locked in 95 open position by means of the lug *g* engaging the slot *i* of the head portion *m* of the casting *j*, and in order to unlock the leg so that the same may be folded, the operator moves the handle element *o* in the direction 100 of the arrow *s*, as shown in Figs. 4 and 5, whereby the lug *g* is moved out of engagement with the slot *i*. When the slide *f* has been moved so that the head portion *m* is in the position between the lugs *g* and *h*, the 105 leg may be folded, as shown in Fig. 3; then by a further movement of the handle *o* in the same direction, the lug *h* is brought into

engagement with the slot *i* in the head portion *m*, thus locking the leg.

To open the leg it is only necessary to reverse the above described operations.

5 From the foregoing description, it will be seen that I have produced a very simple and efficient table-leg locking device and one that readily permits the leg to be locked securely in both an open and folded position.

10 What I claim, is:—

1. In a locking device for table legs comprising a casing element adapted to be secured to the under side of the top of a table, a leg foldably attached to the table-top, a casting having a head portion and secured thereto and provided with a groove in the head portion thereof, a slide mounted within the casing element and having a pair of lugs, said lugs being arranged to enter the groove

in the casting, whereby the leg may be 20 locked in either the open or folded position.

2. In a locking device for table legs comprising a casing element adapted to be secured to the underside of the top of a table, a leg foldably attached to the table-top, a 25 casting having a head portion and secured thereto, and provided with a groove in the head portion thereof, a slide mounted within the casing element and having a pair of lugs, said lugs being arranged to enter the groove, 30 in the casting, whereby the leg may be locked in either the open or folded position, means for operating the slide, and a latch for locking the slide.

CORNELIUS C. HASTINGS.
